UNITED STATES PATENT OFFICE.

WARREN H. TAYLOR AND THOMAS DONAHUE, OF STAMFORD, CONN.

IMPROVEMENT IN CURTAIN ROLLERS AND BRACKETS.

Specification forming part of Letters Patent No. **170,205**, dated November 23, 1875; application filed November 10, 1874.

To all whom it may concern:

Be it known that we, WARREN H. TAYLOR and THOMAS DONAHUE, of Stamford, in the county of Fairfield and State of Connecticut, have invented new and useful Improvements in Curtain-Fixtures, which improvements are fully set forth in the following specification, reference being had to the accompanying drawings.

Our invention relates to improvements in curtain fixtures or brackets adapted to receive, support, and control the movement of curtain-rollers, the nature of which will be fully described by reference to the accompanying drawings, which form part of this specification.

Figure 1 represents a front view of part of a window-casing with a curtain, roller, and fixtures applied thereto. Fig. 2 is a side view of a right-hand, and Fig. 3 a similar view of a left-hand, fixture or bracket. Fig. 4 shows detail views of parts of a bracket or fixture; and Fig. 5 an end view of a curtain-roller and parts connected therewith.

In each of the views similar letters of reference are employed to indicate corresponding parts wherever they occur.

a represents a window-curtain, which is supported with capability of being wound upon a roller, *a*¹, the ends of which are provided with caps *a*² *a*³, formed with axles *a*⁴ *a*⁵, the axle *a*⁴ being affixed to the cap *a*², while the axle *a*⁵ is attached to the end of the pulley *a*⁶, formed on the end of the cap *a*³. *b* is the left-hand bracket, the extension *b*¹ of which is formed with a vertical slot, *b*², for the reception of the axle *a*⁴, and a hole, *b*³, for the passage of a screw, as hereinafter explained. *d* represents the base-plate of the bracket, which is formed at right angles to the extension *b*¹, and provided with an elongated slot, *d*¹, for the passage of a screw. *e* *e* *e* *e* are pairs of spurs or projections, formed on the adjacent extremities of the external faces of the extension *b*¹ and base-plate *d*, the spurs *e* *e* being at right angles to the spurs *e* *e*. *c* represents a right-hand bracket, the extension *b*¹ of which is provided at its outer extremity with a loop, *c*¹, for the passage and control of the cord *a*⁷ for operating the roller *a*¹. The extension *b*¹ of the bracket *c* is also provided with a semicircular rim, *c*², formed

with ratchet-teeth *c*³, adapted to engage, when required, with correspondingly-formed teeth on the periphery of the flange *a*⁸ of the pulley *a*⁶ of the blind-roller *a*¹. The extension *b*¹ of the bracket *c* is formed with a screw-hole, *b*³, and spurs *e* *e*, and is affixed to a base-plate, *d*, having an elongated slot, *d*¹, and spurs *e* *e*, similar to those described in reference to the bracket *b*. The slot *b*² of the extension *b*¹ of the bracket *c* is formed triangular, with an extended base, so as to allow of the lateral movement of the axle *a*⁴ of the roller *a*¹ therein. *c*⁴ is a loop, projecting at right angles from the extension *b*¹ of the bracket *c*, adapted to guide and control the cord *a*⁷ in its passage to and from the pulley *a*⁶. The cord *a*⁷, after passing through the loop *c*⁴, is passed through a hole in or otherwise rigidly connected to the pulley *a*⁶ of the blind-roller *a*¹, for the purpose of operating the same by being wound onto or unwound off the same.

By forming the extensions *b*¹ of brackets or fixtures *b* and *c* with screw-holes *b*³ and spurs *e* *e*, and the base-plates *d* with elongated slots *d*¹ and spurs *e* *e*, the spurs *e* *e* and *e* *e* being formed at the extremities of the outer faces of the adjacent ends of the extensions *b*¹ and base-plates *d*, and at right angles to each other, it will be readily seen that our improved brackets or fixtures may be readily applied either to the outer or inner facings of window-casings; and in either instance the extensions *b*¹ will be supported at right angles to and in position for the support of the axles *a*⁴ *a*⁵ of a blind-roller, *a*¹. It will also be seen that in either case one pair of spurs will be inserted in the facing of the window-casing, while the other pair projects over the surface of the same to prevent the tilting of the bracket or fixture.

When applying our improved brackets or fixtures to the outer facing of window-casings the spurs *e* *e* are inserted into the surface, and screws applied through the slots *d*¹, thereby securing the brackets firmly in position, as shown by Fig. 1. When it is desired to affix such brackets or fixtures to the inner facing of the window-casing the spurs *e* *e* are inserted, and screws applied through the holes *b*³.

In applying a roller, *a*¹, provided with a curtain, *a*, to our improved fixtures or brackets the curtain should be first wound tightly onto

the roller a^1 , leaving the cord a^7 unwound from the pulley a^6 . The axle a^5 is then inserted into the angular slot b^1 of the bracket c , and the opposite axle a^4 dropped into the vertical slot b^1 of the bracket b . The cord a^7 should then be placed through the loop c^4 , as shown in Fig. 1. This having been done, the curtain may readily be drawn down by applying slight pressure to the end of the cord a^7 , so as to draw the teeth of the flange a^8 of the pulley a^6 away from the teeth c^3 of the semicircular rim c^2 . When the blind has been drawn down sufficiently the tension of the cord a^7 is removed, and the weight of the curtain a will then draw the axle a^5 of the roller a^1 forward, thereby bringing the teeth of the flange a^8 of the pulley a^6 into contact with the teeth c^3 of the rim c^2 , thereby firmly holding the blind a in position until tension is again applied to the cord a^7 .

In pulling down the curtain a it will be readily seen that the cord a^7 is wound onto the pulley a^6 , and, vice versa, when the cord a^7 is unwound off the pulley a^6 the blind a will be drawn up.

Having thus described our invention, we would have it understood that we do not claim, broadly, the application of spurs to aid in securing curtain fixtures or brackets in position. Nor do we claim, broadly, a blind-roller provided with a ratchet-wheel or surface formed on or affixed to its end, and engaging with a

stop or ratchet, the blind being raised and lowered by means of a cord capable of being wound onto or unwound off a pulley or surface formed on the end of the blind-roller; but

What we do claim, and desire to secure by Letters Patent, is—

1. A curtain fixture or bracket constructed with an extension, b^1 , provided with a slot, b^2 , and screw-hole b^3 , a base-plate, d , formed at right angles to the extension b^1 , and provided with a slot, d' , and having spurs or projections $e e e' e'$ formed at the extremity of the adjacent ends of the external faces of the extension b^1 and plate d , and at right angles to each other, the whole being constructed as and for the purpose described.

2. The combination, with a curtain fixture or bracket constructed with an extension, b^1 , slot b^2 , screw-hole b^3 , loop c^4 , base-plate d , slot d' , and spurs or projections $e e e' e'$, of the semicircular rim c^2 , provided with ratchet-teeth c^3 , the whole being constructed as and for the purposes specified.

In testimony that we claim the foregoing as our own invention we affix our signatures in presence of two witnesses.

WARREN H. TAYLOR.
THOMAS DONAHUE.
